UNITED STATES PATENT OFFICE.

HENRY A. ADAMS, OF SANDWICH, ILLINOIS.

CORN-SHELLER.

SPECIFICATION forming part of Letters Patent No. 252,594, dated January 24, 1882.

Application filed June 6, 1881. (No model.)

To all whom it may concern:

Be it known that I, HENRY A. ADAMS, a citizen of the United States, residing at Sandwich, in the county of De Kalb and State of Illinois, have invented certain new and useful Improvements in Corn-Shellers, which are fully set forth in the following specification, reference being had to the accompanying drawings, in which—

10 Figure 1 represents a side elevation of a portion of the shelling devices sufficient to illustrate my invention; Fig. 2, a plan section of the same, taken on the line $x-x$, Fig. 1; Fig. 3, a cross-section of my improved straight runner on an enlarged scale, taken on the line $y-y$, Fig. 1.

15 My present invention relates to an improvement in the construction of the shelling devices generally employed in corn-shellers, an illustration of which may be seen in a prior patent granted to me October 15, 1872, No. 132,128.

20 The invention consists in a bevel on the toothed face of the shelling wheel or disk called the "straight runner," on the outer portion of this face, so that the outer teeth will be gradually withdrawn slightly from the plane of the rest of the teeth.

25 The general construction of corn-shelling machines is so well-known, and has been shown and described so frequently in prior patents, that it is not necessary to illustrate the entire machine in the drawings, and therefore I have restricted my drawings to the shelling mechanism and have shown only so much of this mechanism as is necessary to a complete understanding of my present improvement, which I will now proceed to describe.

30 In the drawings, A represents the shelling wheel or disk called the "straight runner." Two of them are shown, each provided on one face with the ordinary teeth or projections, a , and both being mounted on the same shaft B. The usual bevel runners, C, two of which are shown in the drawings mounted on the shaft D, are arranged in the ordinary relation to the straight runners.

45 As heretofore constructed the straight runners have had substantially straight even faces, so that the teeth would all stand in the same plane. In my improvement the teeth a' of two or three of the outer rows are retracted or withdrawn from the plane of the other teeth. This

I accomplish by making the straight runner with a slight bevel near its outer edge, as clearly shown in Figs. 2 and 3 of the drawings. The teeth a' should stand perpendicularly to the main face of the runner, the same as the other teeth; and in order to secure this result easily I make the bevel by a series of steps, a^2 , each one of which recedes a little farther than the other and carries a row of teeth. These teeth, being made of the same length as the others, will of course leave their points gradually receding from the plane in which the ends of the main body of teeth are situated. Obviously, therefore, a flaring opening will be made between the outer portion of the straight runner and the bevel runner, as shown in Fig. 2 of the drawings. This is intended to obviate a difficulty which has been experienced where the faces of the straight runner are straight, so that the teeth all lie in the same plane. It has been found that the opening between the straight runners and the bevel runners is so small that ears of corn, especially if somewhat damp, do not readily enter, but are thrown back. With my improvement this difficulty is entirely removed, as the flaring of the opening between the outer edge of the straight runner and bevel runner is sufficient to readily receive the end of an ear of corn, so that it will be taken at once by the teeth, after which there is no difficulty.

50 To provide for the beveling of the straight runners I have shown them with the outer portion offset, though of course the result may be accomplished some other way, and I do not limit myself to any particular mode of making the bevel. So, too, the beveled face need not be stepped, though this is the preferable construction in my opinion; and if the teeth of the straight runners are quite long, it may be sufficient to simply shorten those in the outer rows without changing the plane of the disk-body.

55 I have shown and described what I consider the best mode of carrying out my invention; but I do not wish to be understood as limiting my improvement to the precise construction here described, but claim the right to make such modifications as suggested above and others of like nature.

60 It will of course be understood that in a machine having several "holes" my improvement will be applied to both faces of the bevel run-

ners, and that it may be used in any machine having straight runners and bevel runners for its shelling mechanism.

Having thus described my invention, what I claim as new, and desire to secure by Letters Patent, is—

1. In a corn-sheller, a straight runner having the points of its outer teeth gradually receding, substantially as described.
2. In a corn-sheller, a straight runner provided with gradually-receding teeth on the outer portion of its face or faces, in combination with bevel runners, substantially as and for the purpose set forth.

3. A straight runner, A, provided with a 15 bevel in the outer portion of its face, on which are arranged gradually-receding teeth a' , substantially as described.

4. A straight runner, A, provided with a bevel on the outer portion of its face, composed 20 of a series of steps or offsets, a^2 , and having teeth a' , arranged on these offsets, substantially as described.

HENRY A. ADAMS.
